UNITED STATES PATENT OFFICE.

ERVIN M. FITZ, OF WORTHINGTON, OHIO.

AUTOMATIC SWITCH.

1,247,946.

Specification of Letters Patent. Patented Nov. 27, 1917.

Application filed July 11, 1916. Serial No. 108,747.

To all whom it may concern:

Be it known that I, ERVIN M. FITZ, a citizen of the United States, residing at Worthington, in the county of Franklin and State 5 of Ohio, have invented an Improved Automatic Switch, of which the following is a specification.

This invention is an improved switch adapted to be thrown to reverse positions 10 by the reverse movements of a reciprocating body, and intended more particularly for shifting the switch at the beginning of the reverse movements of a revoluble body, being designed for effecting an engagement to 15 make the throw at the beginning of the revolution in each direction and for adjustment to avoid further engagement in the continuous revolution while the throw is effective.

A primary object of my invention is to 20 maintain constant polarity of current at the brushes of generators having armatures driven in reverse directions, and a particular use is found in charging storage batteries for lighting trains by axle generators of cars 25 or rolling stock commonly moved in reverse directions.

A characteristic embodiment of my improvements is found in the combination of a 30 double pole double throw knife blade switch mechanism connected to the field mechanism of a generator, with a ball movable in a cam way of an oscillatory carrier connected with the revolving armature.

The nature and characteristic features of 35 my invention are fully disclosed in the following description and the accompanying drawings in illustration thereof.

In the drawings, Figure 1 is a sectional side elevation of mechanism embodying my 40 invention; Fig. 2 is a sectional side elevation of the same mechanism in a second position; Fig. 3 is a sectional view taken on the line 3—3 of Fig. 1; Fig. 4 is a sectional view taken on the line 4—4 of Fig. 2; Fig. 5 is a 45 sectional view taken on the line 5—5 of Fig. 2; Fig. 6 is a plan view of the switch actuator, and Fig. 7 is a diagrammatic view of the electrical mechanism.

In the form and application of my invention illustrated in the drawings, a generator's field frame 1 has connected therewith a double pole double throw switch comprising the terminals 2 and 2^a connected with the field winding 3 by the respective conductors 3^a and 3^b, the terminals 2^b and 2^c connected with the terminals 2 and 2^a by the respec-

tive conductors 4 and 4^a, and the blades 5, 5^a, 5^b and 5^c fixed to a shaft 6 which is journaled in the bearing 7 and adapted for throwing the blades and making and breaking contact with the respective terminals 2, 2^a, 2^b and 2^c.

The generator's armature 8, revoluble about an axis parallel to that of the switch, has its respective brushes 9 connected by the 65 conductor 9^a with the integrally connected blades 5 and 5^a and by the conductor 9^b with the integrally connected blades 5^b and 5^c, which are insulated from the blades 5 and 5^a.

The switch actuator comprises a block or 70 carrier 10 connected to the armature ring 8' by the pivot 11 providing it with an axis of oscillation parallel to the axis of the armature, the ring being provided with bearings 8'' between which the carrier oscillates and 75 which support the springs 12 acting against its opposite sides to restore it to and holding it in normal position.

The carrier 10 is provided with the parallel peripheral grooves 10' and 10'' in the planes of the respective cams 5' and 5'' of the respective blades 5^b and 5, the outer race or cam way sections 10^a and 10^b in the planes of the respective grooves, the inner race or cam way section 10^c in a plane midway between the planes of the sections 10^a and 10^b, and the inclined transverse race sections 10^d and 10^e connecting the opposite ends of the sections 10^a and 10^b with the respective ends of the section 10^c. A ball 13 is movable in 90 the cam way formed by the sections 10^a to 10^e inclusive.

In operation, with the parts in the relation shown in Fig. 1 and the armature revolving clockwise, the ball 13 (held in the dead end of the race section 10^a to the right of the central plane dividing the symmetrical cam way) engages the cam 5' of the blade 5^b projecting into the groove 10' and rocks the integrally connected blades so that 100 the contacts of the blades 5^a and 5^b with the terminals 2^a and 2^b are made and the contacts of the blades 5 and 5^c with the terminals 2 and 2^c are broken. The force of the impact of the cam or projection 5' and the ball 13 rocks the carrier 10, on its axis 11, anti-clockwise, and projects the ball beyond its normal arc, so that when it passes the cam 5' the latter has been moved beyond the ball when revolving in its normal arc. When 110 the ball 13 has passed the cam 5', the carrier 10 is moved by the compressed spring 12 to

its normal or central position, in which a plane containing the parallel axes of the armature and carrier is symmetrically disposed with reference to the cam way. In 5 this position, the ball 13 clears the cam 5' and the continued clockwise revolution of the armature is without interference between the ball and cam.

When the movement of the armature is 10 reversed or the revolution is anti-clockwise, the ball 13 rolls from the section 10^a, through the sections 10^a, 10^c, and 10^e, into the section 10^b, and strikes the cam or projection 5'' on the blade 5 extending into the way 10'', with 15 the result that the blades are thrown to effect the reengagement of the blades 5 and 5^c with the terminals 2 and 2^c. The impact rocks the carrier, projects the ball outwardly and forces the registering cam 5'' beyond 20 the normal path of the ball. Having passed the blade, the carrier is moved by the compressed spring 12 to its normal position, in which the ball clears the cam 5'' in the further anti-clockwise revolutions of the armature.

When the blades 5^a and 5^b make contact with the terminals 2^a and 2^b, current flows in the closed circuit comprising the conductors 8, 9^a, 5^a, 2^a, 3^a, 3, 3^b, 2, 4, 2^b, 5^b and 9^b. 30 When the blades 5 and 5^c make contact with the terminals 2 and 2^c, current flows through the closed circuit comprising the conductors 8, 9^a, 5, 2, 3^b, 3, 3^a, 2^a, 4^a, 2^c, 5^c, and 9^b. In the different positions of the switch, the direction of the current through the field winding 3 is reversed, with the results desired.

Having described my invention, I claim:

1. The combination with a switch, of an 40 actuator, and a revoluble device on which said actuator is adapted to oscillate, said actuator comprising a carrier having a cam way and means movable to different positions in said cam way in reverse movements 45 of said device, whereby said switch is shifted to reverse positions.

2. The combination with a switch having oscillatory means comprising a blade, of an actuator, and a revoluble device to which 50 said actuator is eccentrically pivoted, said actuator comprising a carrier provided with a cam way and a ball movable in said cam way so as to rotate in different parallel

planes to engage said means and reverse said blade in the reverse movements of said device, whereby said actuator is rocked, said ball is projected beyond its normal position and said means moved beyond the normal path of said ball.

3. The combination with a switch having 60 oscillatory contact making and breaking means, of an actuator therefor, means movable in reverse directions with which said actuator has an oscillatory connection, said actuator comprising a device movable relatively thereto for operating said means first named, and means for bringing the deflect- 65 ed actuator to normal position.

4. The combination with a switch having 70 oscillatory contact making and breaking means, of an actuator for rocking said means in reverse directions, a device movable in reverse directions to which said actuator is connected in oscillatory relation, and means comprising a spring for bringing 75 the actuator deflected by contact with said means to normal position in a path removed from said means.

5. The combination with a switch having 80 a plurality of connected blades, of a rotary device having an actuator pivoted eccentrically thereon, said actuator comprising a carrier provided with grooves registering with said blades, a cam way having terminal sections registering with said grooves, 85 and a ball movable along said cam way into different terminal sections to positions for reversely operating said blade on reversing said device.

6. The combination with a generator having 9 a stationary field mechanism, and a rotary armature mechanism, of a double pole double throw switch fixed to said field mechanism and a switch actuator connected to said armature mechanism, said actuator comprising a ball carrier connected in movable relation to said armature mechanism, and a ball movable to different positions relative to said carrier by the reversal of the direction of rotation of said armature 1 mechanism, whereby the position of said switch is reversed with said reversal.

In testimony whereof I have hereunto set my name this 27th day of June, 1916.

E. M. FITZ.
